US00D681885S

(12) **United States Design Patent**
Pitter

(10) **Patent No.:** **US D681,885 S**
(45) **Date of Patent:** **** May 7, 2013**

(54) **FEEDING DEVICE FOR ANIMALS**

(75) Inventor: **Dan Pitter**, Rotherwick (GB)

(73) Assignee: **Elite Dogstands Ltd.**, Harlow (GB)

(**) Term: **14 Years**

(21) Appl. No.: **29/383,604**

(22) Filed: **Jan. 20, 2011**

(30) **Foreign Application Priority Data**

Jul. 23, 2010 (EM) 001735606-0001

(51) **LOC (9) Cl.** **30-03**

(52) **U.S. Cl.**

USPC **D30/129**; D30/130; D30/128; D30/133;

(57) **CLAIM**

The ornamental design for a feeding device for animals, as shown and described.

DESCRIPTION

FIG. 1 is a perspective view from above of my new feeding device for animals of FIG. 1;

FIG. 2 is a top plan view of my new feeding device for animals of FIG. 1;

FIG. 3 is an underneath view of my new feeding device for animals of FIG. 1;

FIG. 4 is a side view as seen from the right side of my new feeding device for animals of FIG. 1, the left side being a mirror image thereof;

FIG. 5 is a front view of my new feeding device for animals of FIG. 1; and,

FIG. 6 is an exploded perspective view of my feeding device for animals of FIG. 1.

1 Claim, 6 Drawing Sheets
